Des. 1129

To all whom it may concern:

Be it known that I, Elenor J. Fay, of Lowell, in the County of Middlesex and State of Massachusetts have originated and designed a new pattern for Carpets or other fabrics, of which, the following is a full, clear and exact description, reference being had to the accompanying drawings making part of this Specification.

A. L. 3 & 4, in the corners, are leaves, bordered with sprigs, each resting on a quarter of the plane fig. A.

B. in the center is a figure formed of scrolls, and resting on a plane ground.

C. at the sides and D. at the ends, when matched form figures similar to each other, and lying at equal distances from center and corners, the branches 5, and leaves 6, run from D. to C. and cover the remaining portions of the design.

The colors employed for the different portions of the design, may be varied to suit the taste and wish of the manufacturer.

CLAIM.

What I claim as my invention, and desire to secure by letters patent, is the design or pattern for Carpets herein set forth.
